UNITED STATES PATENT OFFICE.

ALFRED R. WILSON, OF DETROIT, MICHIGAN, ASSIGNOR, BY MESNE ASSIGNMENTS, TO HUTCHINS CAR ROOFING COMPANY, OF DETROIT, MICHIGAN, A CORPORATION OF DELAWARE.

SADDLE AND CENTER JOINT CAP.

Application filed April 5, 1926. Serial No. 99,948.

This invention relates to combined running board saddle and center joint cap and has as one of its principal objects to construct such a device as a unit and further to provide a construction which is entirely weatherproof.

The invention has also as its object to simplify, render more efficient, and improve generally devices of this character and these, as well as other objects, advantages and novel details of construction, will be made more apparent as this description proceeds, especially when considered in connection with the accompanying drawings wherein

Figure 1 is a fragmentary plan view of a car roof showing my invention in use.

Figure 2 is a fragmentary sectional view taken substantially on the line 2—2 of Figure 1.

Figure 3 is a fragmentary sectional view indicated by the line 3—3 of Figure 1.

Figure 4 is a fragmentary perspective view showing more in detail this improved device.

Referring now particularly to the drawings wherein like reference characters indicate like parts, it will be noted that there is shown a ridge pole 10 and a carline 11 of the roof frame, the latter being shown as of a substantially inverted U-shape and further as secured to the ridge pole by means of bolts 12. The roof sheets 13 in the herein illustrated construction are formed of metal and are adapted to be loosely supported to provide a flexible roof structure and are therefore formed with upstanding flanges 14 on their inner and side edges adapted for cooperation with ridge caps 15 and carline caps 16 respectively, in the customary manner, for weather-proofing the joints between the transverse and longitudinal adjacent roof sheets.

The structure forming the particular subject matter of this invention affords means for weather-proofing the junction of the ridge caps and carline caps and further for affording means for supporting the running board. To this end there is provided a center joint cap member 17 suitably shaped to form cross channel shaped portions adapted to embrace the adjacent ends of the carline caps and ridge caps respectively. For this purpose the center joint cap is formed with a pair of channel-shaped portions 18

which extend in the direction of the carline caps 16 and are adapted to overlap and straddle the adjacent ends of these carline caps in the manner shown more particularly in Figure 2. The center joint cap is formed also with the transversely extending channel portions 19 which are adapted to overlap and straddle the adjacent ends of the ridge caps 15 as more clearly shown in Figure 3.

The channel portions 18 and 19 merge into a substantially horizontal center portion 20, the channel portions 18 being inclined downwardly therefrom to a degree coincident with the inclination of the roof from the ridge pole to the eaves. When the center joint cap 17 is secured in place as described, the juncture of the ridge caps and carline caps is weather-proof and for further weather-proofing the connection, a canvas sheet or washer 21 may be positioned so as to extend entirely under the cap member 17, this washer also eliminating the direct metal to metal engagement between the parts which would otherwise result.

The center joint cap is provided with spaced upwardly directed extensions 22 terminating in the horizontal flanges 23. The saddle plate 24 rests upon these horizontal flanges 23 and is provided adjacent its center with a downwardly directed offset or depression forming a slot or recess 25 and providing a wall portion 26 parallel to the portion 20 of the center joint cap out of the general plane of the saddle plate. Thus, an engagement between the center joint cap and saddle is not only effected at the ends of these parts but also at the center thereof. At this point of central engagement these two members are apertured to receive the neck 26' of a shouldered bolt 27, the shoulder 28 of which bears against the under side of the center joint cap. The head of this bolt is riveted over as shown at 29 to rigidly and tightly unite the center joint cap and saddle plate and to weatherproof the apertures formed in these members through which this bolt projects. This saddle bolt 27 is adapted to extend downwardly through suitable apertures formed in the ridge pole 10 and the adjacent carline 11 and is threaded to receive a nut 30. The running boards 31 rest upon the saddle plate 24 and are secured in place by means of bolts 32, certain ones of which also pass through the

horizontal flanges 23 of the center joint cap for securing the saddle plate thereto at these points.

The invention is distinguished by the fact that it may be cheaply manufactured, distributed as a unit and also installed as a unit thus greatly facilitating installation. Furthermore, adequate water-proofing of the apertures for receiving the bolt 24 is provided without the introduction of special water-proofing means which might otherwise complicate or increase the cost of production of the structure.

Reservation is, of course, made to make such changes in the details of construction as may come within the purview of the accompanying claims.

What I claim as my invention is:

1. In a car roof, a center joint cap, a saddle plate and a saddle bolt affording means for uniting said cap and plate to form a unitary structure and for securing said parts to the roof structure.

2. In a car roof, a center joint cap, a saddle plate and a shouldered bolt riveted in place for securing said cap and plate together.

3. In a car roof, a ridge pole a center joint or junction cap, a saddle plate, said cap and plate being formed with engaging parallel portions and a saddle bolt riveted to the said parallel portions and securing said cap and plate to said ridge pole.

4. In a car roof, a junction cap, upwardly extending projections on said cap, a saddle plate formed with a downwardly extending projection adapted to engage said cap at a point intermediate the projections thereon and means for securing said cap and plate together spaced apart by said projections.

5. In a car roof, a carline a center joint cap, a saddle plate, said cap and plate having engaging portions formed with aligned apertures and a saddle bolt passed through

said apertures and riveted to said cap and plate the said saddle bolt securing the said cap and plate to the said carline.

6. In a car roof, a center joint cap, a saddle plate, said cap and plate having engaging portions formed with aligned apertures and a shouldered bolt having a portion extending through said aligned apertures with the shoulder thereof engaging one of said members, the end of said bolt being headed to cooperate with said shoulder to secure said cap and plate together.

7. In a car roof, a center joint cap formed with spaced upwardly extending projections, a saddle plate resting on said projections and formed with a downwardly extending depression engaging said cap and a shouldered bolt passed through aligned apertures in the engaging portions of said cap and plate and riveted in place.

8. In a car roof, a center joint cap formed with spaced upwardly extending projections, a saddle plate resting on said projections and formed with a downwardly extending depression engaging said cap and a bolt formed with a shoulder engaging the underside of said cap and extending through aligned apertures in the engaging portions of said cap and plate and provided with a riveted head cooperating with said shoulder for securing said parts together.

9. In a car roof, a carline, a ridge pole a center joint cap, a saddle plate and a member having a head portion rigidly securing the said cap and plate together whereby the said cap and plate may be installed on and removed from a roof structure as a unit, the said member also having a body portion engaging the said carline and ridge pole for securing the cap and plate to the carline and ridge pole.

In testimony whereof I affix my signature.

ALFRED R. WILSON.
